UNITED STATES PATENT OFFICE.

HARRISON T. NOBLE, OF CLINTON, ILLINOIS.

WASHING-MACHINE.

SPECIFICATION forming part of Letters Patent No. 231,842, dated August 31, 1880.

Application filed July 3, 1880. (No model.)

To all whom it may concern:

Be it known that I, HARRISON T. NOBLE, of Clinton, in the county of Henry and State of Missouri, have invented a new and valuable Improvement in Washing-Machines; and I do hereby declare that the following is a full, clear, and exact description of the construction and operation of the same, reference being had to the annexed drawings, making a part of this specification, and to the letters and figures of reference marked thereon.

Figure 1 of the drawings is a representation of a top view of my improved washing-machine. Fig. 2 is a vertical central section of the same, and Fig. 3 is a detail.

This invention has relation to improvements in that class of washing-machines wherein the tub is given an opposite rotary motion from the scrubber, and the object of the invention is mainly to increase the rotary or oscillatory play of the tub and scrubber without materially increasing the effort required to produce such movements, and to regulate the play at pleasure, according to circumstances; and it consists in the construction and novel arrangement of parts, as hereinafter shown, described, and particularly pointed out in the claim.

In the accompanying drawings, the letter A designates a frame composed usually of two bases, *a*, a bar or beam, *b*, connecting said bases, and provided with converging conduits *c*. The beam *b* affords bearings to a spindle, *b'*, of a tub, *B*, and of two parallel uprights, *C* *C'*. The tub *B* is constructed in the usual way, and is permanently secured to a frame, *B'*, from which the spindle *b'* projects. The tub has, therefore, free horizontal vibration, and it is provided with metallic eyes *b''*, that extend up through slots in a false bottom, *A'*, which is secured to the tub by means of latches *l* on the same, which engage the said eyes. The false bottom may be removed, if desired, by disengaging the latches from the eyes and then lifting it out of the tub. It is provided with raised ribs *d* *d'* *d''* *d'''*, arranged nearly radially, and with ribs *e* *e'* *e''* at right angles to the same, all of which are readily removable when worn out, and it rests upon the cleats or battens *f* in the bottom of the tub. These battens slightly raise the false bottom and al-

low dirty water ready access to a vent, *f'*, in the bottom of the tub.

D indicates a circular scrubber having on its under side raised ribs, not differing from those of the false bottom aforesaid. I do not, however, confine myself to any special form of rib, or to any special arrangement thereof, either on the false bottom or on the scrubber, as any species of corrugation or roughening of the rubbing-surfaces of the same will serve 60 a good purpose.

The scrubber has rigidly secured to it a vertical shaft, *D'*, having its bearings in a cross-bar, *E*, connecting the upper ends of the uprights *C* *C'*. This bar is hinged to upright *C* 65 and removably secured to the upright *C'* by means of a pin, *g*, extending through the end thereof obliquely and engaging an eye, *g'*, on the upright *C'*.

The shaft *D'* has on its upper end a crank, *F*, having a number of perforations, *h*, arranged at intervals, which crank is connected by means of a pitman, *G*, to a walking-beam lever, *G'*, fulerumed to vibrate vertically on a stud, *g''*, of upright *C*. The lower end of the 75 lever *G'* is connected by a pitman, *H*, to the frame *B'*, on which the tub is fixed. Fulerumed by its lower end to the stud *g''* is a vertically-vibrating operating-lever, *I*, connected to the walking-beam lever *G'* by the link *J*. This 80 link is permanently pivoted to the beam-lever at a point intermediate to its fulcrum and its upper end, and is adjustably secured by a pin, *h'*, to the hand-lever *I*, which has a number of perforations, *i*, for the purpose. The vibration of lever *I* imparts a rocking or oscillating motion to the beam-lever, which, by means of the pitmen *G* *H*, gives the tub and scrubber a to-and-fro movement in opposite directions. The pitman *G* is permanently secured to the 85 walking-beam lever at its upper end, and is adjustably connected to the crank *F* by means of a hook, *h''*, on the end of said pitman, that engages one or the other of the perforations *h* of the said crank.

The articles to be washed are spread upon the false bottom *A'* and subjected to a vigorous rubbing from the scrubber.

I am aware that a washing-machine having a corrugated scrubber and tub oscillating in 100

opposite directions is not broadly new, and I therefore make no claim to such devices.

Upon the upper end of the post C' is rigidly attached a trough, K, overhanging the tub, 5 and designed for the attachment of a wringer, the trough carrying the drip back into the tub.

The scrubber is lifted out of the tub by swinging the cross-beam upward on its hinge. This hinge is of peculiar construction. It is formed 10 by means of a metallic plate, l, inserted end-wise in a deep cleft, o, of upright C, and pivoted to the said upright by means of a pin, m. Its remaining end is inserted in a cleft, o', of the cross-bar E and pivoted thereto by means 15 of a pin, m'. The plate l allows the cross-bar to be thrown up and to carry the scrubber with it, when, being thrust down, the said plate allows the said bar to be placed in the position indicated in Fig. 2 and to bear on the upper 20 end of the upright C, which is thus made to serve as a prop to sustain the cross-bar and scrubber while the clothes are spread on the false bottom A'.

What I claim as new, and desire to secure by Letters Patent, is—

A washing-machine consisting of the stand A, having uprights C C', the former provided with stud g², the hinged cross-bar E, the tub B, pivoted to rotate horizontally on said stand, and the scrubber D, having the shaft D', journaled on said cross-bar, and provided with crank-arm F, the lever G', pivoted to said stud, the pitmen G H, pivoted, respectively, to the upper and lower ends of lever G' and to the crank-arm F and tub-frame B', the operating-lever I, having perforations i, pivoted to stud g², and the link J, pivoted to pitman G and adjustably pivoted to the operating-lever by means of pin h', substantially as specified.

In testimony that I claim the above I have 40 hereunto subscribed my name in the presence of two witnesses.

HARRISON T. NOBLE.

F. E. SAVAGE.

Correction for Letters Patent No. 231,842.

It is hereby certified that in Letters Patent No. 231,842, dated August 31, 1880, to Harrison T. Noble, for Improvement in "Washing Machines," the domicile of the patentee was erroneously written and printed in said Letters Patent Clinton, Illinois, instead of Clinton, Missouri; that the proper corrections have been made in the records of this Office, and that said correction is hereby made in the Letters Patent.

Signed, countersigned and sealed this 17th day of December, A. D. 1880.

[SEAL.]

A. BELL,

Acting Secretary of the Interior.

Countersigned:

E. M. MARBLE,

Commissioner of Patents.
